UNITED STATES PATENT OFFICE.

KATHERINE SCHMUTZLER, OF GLENSIDE, PENNSYLVANIA.

LADY'S COMBINATION UNDERGARMENT.

Application filed June 3, 1927. Serial No. 195,892.

The main object of the invention is to provide an undergarment for feminine use which by its construction and design eliminates the generally used camisole, drawers and petticoat, all of which are used at the same time but are draped on the body individually. To be properly dressed when using these articles of apparel a great amount of time is spent in donning them and the garment of the invention aims to eliminate some of this time by providing a garment which answers the same purpose as the three garments and at the same time is donned as a unit.

The above and other objects will become apparent in the description below in which like characters of reference refer to like-named parts in the drawing.

Referring briefly to the drawing, Figure 1 is a front elevational view of the garment showing a portion thereof broken away to illustrate the construction of the crotch covering.

Figure 2 is a rear elevational view of the garment with a portion thereof broken away to illustrate the interior construction.

Figure 3 is a front elevational view of one section of the garment in blank form.

Figure 4 is a front elevational view of the remaining section of the garment showing the same in blank form.

Referring in detail to the drawing, the numeral 10 indicates the upper portion of the T-shaped section of the garment. The sides of this portion 10 are tapered and diverge downwardly, and this portion bounded by these sides is adapted to cover the upper half of the front portion of the body from the waist to the neck. A rectangular expanse of material 11 is formed integral with the portion 10 and is of sufficient length to completely girdle the body from the waist down to the skirt line and serves as a petticoat. The upper corners 12 and 13 of the petticoat 11 are stitched to each other and in such manner that the side edges 14 of the petticoat overlap each other; as is illustrated in Figure 3. At the position where the portion 10 joins the material 11 the waist line is formed and at a position slightly below this waist line but extending parallel thereto, a longitudinal strip 15 is secured to the petticoat by a row of stitching 16 which secures the upper edge of the strip 15 to the petticoat. At each corner of the strip 15 a button 17 is sewed.

A substantially square section of material 18 of the same dimensions as the portion 10 is used to complete the garment. The lower end of this section 18 has a tapering tab 19 secured thereto by a row of stitching 20. The free end of the tab has the narrowest width and at the corners of the free ends buttonholes 21 are formed.

In the assembly of the garment, the section 18 is superimposed over the portion 10 and the diverging sides of these members 10 and 18, indicated by the numeral 22 are stitched to each other. The edges 14 of the lower portion 11 of the one section are lapped and secured in such relation by stitches formed at their upper ends. The sections after being assembled by stitching provide a garment in which the tab 19 hangs normally downward when the same is not worn and may be conveniently ironed. As worn the garment takes the place of three articles of apparel. The upper portion 10 and the section 18 stitched to it serve as a covering for the upper half of the body and has a use similar to a camisole. The lower portion 11 of the section shown in Figure 3 serves as a petticoat, and the tab 19 when attached by the buttons 17 to the strip 15 serves as a crotch guard and passes between the legs of the wearer thereby substituting for a pair of bloomers.

It is to be noted that certain changes in form and construction may be made without departing from the spirit and scope of the invention.

I claim:

A garment of the class described comprising an inverted T-shaped section of material consisting of an upper tapering portion and a lower longitudinal section of material, the juncture of both portions serving as the waist line, a strip having spaced apart buttons thereon secured to the longitudinal section below the waist line, an additional section of material of the same dimensions as the upper portion of the T-shaped section secured to the latter by stitching, a tab having a tapering outline and having its upper end secured to the additional section, said tab having buttonholes formed therein adapted to engage the buttons on the strip, the upper corners of the longitudinal portion being secured in overlapped relation to form a concealed slit.

In testimony whereof I affix my signature.

KATHERINE SCHMUTZLER.
